UNITED STATES PATENT OFFICE.

CHRISTIANA V. TURNER, OF NICOLA VALLEY, BRITISH COLUMBIA, CANADA,
ASSIGNOR OF ONE-HALF TO DAVID K. McMULLEN, OF SAN FRANCISCO,
CALIFORNIA.

CLASP FOR CORSET-STIFFENERS.

SPECIFICATION forming part of Letters Patent No. 253,642, dated February 14, 1882.

Application filed May 19, 1881. (Model.)

To all whom it may concern:

Be it known that I, CHRISTIANA V. TURNER, of Nicola Valley, British Columbia, Canada, have invented an Improvement in Clasps for 5 Fastening Corset-Stays; and I hereby declare the following to be a full, clear, and exact description thereof.

My invention relates to a device for fastening the whalebones or stiffeners in corsets and for 10 protecting the corsets from the wear of the ends of the stiffeners; and it consists of a small metal clip having points which pass through the cloth on each side of the stiffeners and are clamped behind, the top being provided with an extension for the insertion of an eyelet, and the whole 15 device being pressed down upon and on both sides of the stiffener, all of which will hereinafter more fully appear, reference being made to the accompanying drawings, in which—

20 Figure 1 shows a view of my fastener. Figs. 2 and 3 show its application, front and rear, to the stiffener. Fig. 4 shows its application to a corset. Fig. 5 is a longitudinal section through the clip applied. Fig. 6 is a cross-section on the line *x x* of Fig. 5.

25 Let A represent a section of a corset, having the usual places for the insertion of the whalebones or stiffeners B B, which are here shown.

Let C represent my clasp or fastener, being 30 made of a piece of any suitable soft metal—such as brass—of a somewhat elongated shape, and having a head, *a*, which is perforated, as shown at *c*. Its sides are provided with the sharp points *e e*. The body of the fastener—that is, that portion included between the dotted lines *i i*—is made about the width of the whalebone or stiffener.

35 To apply the fastener I put it on the outside of the corset at the top of the stiffener, so that 40 its extended head *a* will project above the top of the stiffener, the stiffener terminating before reaching the hole *c*. The points *e e* are pushed through the corset on each side of the stiffener and are clamped on the inside, thus securing 45 the device to the corset. I then press down the sides outside of the dotted lines *i i* with the aid of any suitable tool, as a pair of pinch-

ers or pliers, so that a socket is formed containing the end of the stiffener, the sides of which are inclosed and held securely. An eyelet, E, is placed in the corset through the hole 50 *c* at the top of the fastener.

This device has for its object the holding of the stiffeners in place and the prevention of wear by means of the ends of the stiffeners 55 being forced through the cloth. By clamping the stiffener on both sides and by having the eyelet E above, the stiffener cannot move up or slip down. It cannot wear through the cloth on the front side because of the metal clip, and 60 it cannot wear through on the inner side because the metal fastener will not allow the cloth to bend at the end of the stiffener. It can bend only above the eyelet, and as the end of the stiffener does not reach to the point it cannot 65 wear it away.

I am aware that devices for securing the stiffeners of corsets have been used. Eyelets above have been used to prevent it from slipping up, and small clamps the points of which pass 70 through holes in the stiffener are known. Neither of these devices protects the corset from wear at the ends of the stiffener, and in the former the stiffener can slip down, while in the latter it is inconvenient to make holes in it to 75 receive the points of the clamp, and when whalebone is used it is liable to split, and thus prevent it from being firmly secured.

Having thus described my invention, what I claim as new, and desire to secure by Letters 80 Patent, is—

The device for securing the stiffeners in corsets and protecting the cloth from wear at the ends of the stiffeners, consisting of the clasp or fastener C, having a perforated head, *a*, 85 fitted with an eyelet, E, and having the points *e e*, when constructed and adapted to be applied substantially as herein described.

In witness whereof I have hereunto set my hand.

CHRISTIANA V. TURNER.
